UNITED STATES PATENT OFFICE.

EDWARD ARTHUR BROWNFIELD, OF HARTWELL HALL, BARLASTON,
COUNTY OF STAFFORD, ENGLAND.

DESIGN FOR A PITCHER OR VASE.

SPECIFICATION forming part of Design No. 17,426, dated July 5, 1887.

Application filed October 11, 1886. Serial No. 215,943. Term of patent 3½ years. Registered in England December 10, 1885, No. 39,334.

To all whom it may concern:

Be it known that I, EDWARD ARTHUR BROWNFIELD, a subject of the Queen of Great Britain, residing at Hartwell Hall, Barlaston, 5 Stafford county, England, have invented and produced a new and original Design for Pitchers and Vases, of which the following is a specification, reference being had to the accompanying drawing, which forms a part thereof.

1. I have developed in a pitcher the general effect produced by clustered columns in Gothic architecture. The upper portion indicates a cluster composed of four members. The lower portion is scalloped or fluted to correspond, 15 but with a double number of flutes. The whole is wrought in a harmonious design with a horizontal bead extending in a scalloped or wavy line around the junction of the two systems at the largest diameter, another bead extending around a sharply-defined contraction between 20 the body and neck, and two more beads extending around near the top of the slightly flared neck. The top is level.

Referring to the drawing, A is a circular 25 base, and B the lower part of the body, approximately hemispherical, but developed toward the upper and largest part into eight vertical swells or members.

C is a bead extending around the junction of 30 this eight-fluted part B, with the four-fluted part D above. This latter contracts with an approximation to a hemispherical form until its diameter is reduced to about that of the base, where another horizontal fluted bead, E, 35 extends around. Above this rises a neck, F, nearly as high as the body, having the same number of flutes or swells indicating a cluster of four members. This is enlarged at and near the top. The rim is level and finished with a 40 bead, H, a little distance below which is a similar bead, G.

M is a decorative handle made in an ogee curve slightly foliate, and spread at the junctions with the body.

45 I attach importance to the fact that there are but four flutes or members in the main portion of the upper body, D, joining with the

eight flutes in the lower body, B, and that there is a sharply-defined line of junction. This effect may be attained by keeping the line of junction level, and consequently the bead C level, and developing corresponding channels in the lower edge of the upper member, D, which channels shall extend up but a little distance from the junction with B.

By omitting the handle and retaining all the other parts, as shown, a vase is produced having the same general characteristics.

I claim—

1. The design for a pitcher or vase herein shown and described, the same consisting of the narrow cylindrical base-rim A, lower body, B, approximately hemispherical, with eight vertical flutes in its main portion, the approximately-hemispherical upper body, D, having in its main portion four scallops or clustered members, and the tall neck F, fluted or clustered like the upper body and slightly enlarged at the top.

2. The design for a pitcher or vase herein shown and described, the same consisting of the lower body, B, with many flutes or scallops, the upper body, D, with a less number of flutes or clustered members, the wavy bead C along a sharply-defined line of junction, the tall and slightly-flaring neck F, clustered like D, the wavy bead E around the sharply-contracted line of junction, and the two beads G and H at the top.

3. The design for a pitcher herein shown and described, the same consisting of the lower body, B, with many vertical scallops, the upper body, D, with a smaller number of vertical scallops or clustered members, and the tall slightly-flared neck F, fluted or clustered to correspond with the upper body, beaded as shown, and having the decorative and slightly foliate handle M.

EDWARD ARTHUR BROWNFIELD.
